UNITED STATES PATENT OFFICE.

MARIUS DUVALL, OF GOLDFIELD, NEVADA; HELEN DUVALL ADMINISTRATRIX OF
SAID MARIUS DUVALL, DECEASED.

COMBUSTION-ENGINE.

1,295,013.

Specification of Letters Patent. Patented Feb. 18, 1919.

Application filed November 22, 1915. Serial No. 62,723.

To all whom it may concern:

Be it known that I, MARIUS DUVALL, citizen of the United States, residing at Goldfield, county of Esmeralda, State of Nevada, have invented certain new and useful Improvements in Combustion-Engines, whereof the following is a specification.

This invention relates to internal combustion engines, and its object is to improve the construction and operation of the valves of such engines.

In its main features the invention consists in a valve in the form of a cylindrical collar, and in the accessories thereof by which the same is made operative.

In carrying out the invention I apply the cylindrical collar valve, or annulus, against the surface of the engine cylinder, either upon the inside or outside thereof, or intermediate to those positions, and preferably near the top of the same. The valve thus seats upon the circumference of the cylinder. The valve has, preferably, but one port, and the cylinder has two ports. At proper intervals the valve port is opposite, or in register with, the cylinder intake port, to admit the charge into the cylinder, or with the exhaust port, to permit the expulsion of the burnt gases, or with the blank wall of the circumference, when the power and compression strokes take place. The valve is rotated, by suitable connections, from the engine shaft, so that the engine goes through its cycle of suction, compression, combustion and exhaust.

In the accompanying three sheets of drawing I have shown so much of an engine containing my invention, as is necessary to an understanding of the same.

40 In the drawings:—

Figure 1 is an elevation of a portion of a vertical cylinder, with the valve, and the contiguous valve driving gearing.

Fig. 2 is a sectional elevation of the same, taken at right angles to Fig. 1.

Fig. 3 is a top or plan view, the parts being in the position shown in Fig. 1.

Fig. 4 is a cross section, taken on the line *a*, *a*, of Fig. 2.

50 Fig. 5 is an elevation of the valve of the preceding figures, with the driving pinion and a portion of its arbor.

Fig. 6 is a plan view of the same.

Fig. 7 is a partial sectional elevation, on a larger scale, taken on the line *b*, *b*, of Fig. 6.

Fig. 8 is a partial cross section, on a larger scale, taken on the line *c*, *c*, of Fig. 1.

Fig. 9 is a sectional elevation, showing the valve applied to the outer surface of the cylinder, and unhoused except for junk plates at the intake and exhaust manifolds.

Fig. 10 is a sectional elevation showing the valve applied to the inner surface of the cylinder.

Fig. 11 is a cross section taken on the line *d*, *d*, of Fig. 9.

Fig. 12 is a cross section taken on the line *e*, *e*, of Fig. 10.

In these several figures:—

1 is the cylinder of the engine, and 2 the collar valve, applied to the upper part thereof. The valve is housed in a cavity 3 in the end of the cylinder, which may be formed by coring, in the casting thereof, in which case the sides of the cavity are integral with the cylinder, as shown in Fig. 2; or may be otherwise formed. The cavity may be closed at the top, by the cylinder end 4. Near the lower edge of the valve are 80 cut or etched gear teeth 5, with which engage the pinion 6 by which the valve is rotated.

The valve is provided with a single port 7, 7, which is adapted to register at suitable 85 intervals with ports 8 and 9 in the cylinder walls, and which constitute respectively the intake and exhaust ports of the engine. 10 and 11 are the respective manifolds. These parts need not be more particularly described, as their function and action will be readily understood by the mechanic. The valve may be cast of steel, and may be hardened.

The pinion 6 is mounted on an arbor 12, 95 which rotates in bearings 13 and 14, upon the cylinder, and is connected direct with the main shaft and rotated therefrom.

15 is the spark plug, for igniting the charge.

16 are tubes leading from the oil reservoir, which deliver lubricant through openings 17, shown in Figs. 2, 9 and 10, to the top edge of the valve, whence it may pass through channels 18 to the lower edge thereof, as shown in Figs. 5, 6, 7, and 8.

In some cases it may be desirable to provide the valve with knife edges, to more perfectly center it, and reduce wear. Such knife edges I have shown at 19 and 20, in Fig. 9. Also I have shown one such knife edge in Figs. 2, 5, 6 and 7.

Where the valve is unhoused, as in the form shown in Figs. 9 and 11, the operating teeth 5, may be cut upon a rib 21, projecting from the body of the valve.

Where the valve is applied interiorly, as shown in Figs. 10 and 12, it is best operated by a stem 22, projecting into the cylinder from the end thereof, and engaging spokes 15 23 attached to the valve. In this case the pinion 6 engages an auxiliary pinion 24 upon the stem 22, instead of engaging teeth on the body of the valve.

It is believed that the operation of the valve is sufficiently obvious from the foregoing description of its structure, and that further description would obscure rather than enlighten.

Having thus described my invention, and 25 an embodiment of it, in the full, clear and exact terms required by law, and knowing that it comprises novel, useful and valuable improvements in the art to which it pertains, I here state that I do not wish to 30 be limited to the precise construction and arrangement of the several parts, as herein set forth, as the same may be variously modified by a skilled mechanic within the scope of the appended claims without departing from 35 the spirit of the invention.

What I claim and desire to secure by Letters Patent of the United States, is the following, to wit:—

1. In an internal combustion engine, a 40 casing having a V-shaped groove, a cylindrical collar valve having a V-shaped edge engaging said groove.

2. In an internal combustion engine, a cylindrical collar valve having a V-shaped edge, a casing for said valve having an oil 45 channel engaging said V-shaped edge and

adapted to lubricate the bearing faces of said valve.

3. In an internal combustion engine, a cylindrical collar valve having a knife edge, 50 in combination with a cylinder having a corresponding groove for said knife edge and means to rotate said valve.

4. In an internal combustion engine, a cylindrical collar valve fitted and seated 55 upon the exterior surface of the cylinder, said valve being open at its ends and means to continuously center said collar valve.

5. In an internal combustion engine, a cylindrical collar valve having knife edges, 60 said edges engaging corresponding grooves upon the cylinder, in combination with said cylinder and means for rotating said valve.

6. In an internal combustion engine, a cylindrical collar valve, in combination with 65 the cylinder thereof, said valve mounted upon a surface of said cylinder having V-shaped means adapted to centralize said valve.

7. In an internal combustion engine, a 70 cylinder having an annular cavity and a lubricating opening opposite said cavity, in combination with a cylindrical collar valve, in said cavity provided with a knife edge opposite said opening permitting thereby 75 uniform oiling of its bearing faces.

8. In an internal combustion engine, a cylindrical collar valve, mounted upon the exterior face of the engine cylinder, and having a V-shaped edge corresponding with 80 a V-shaped seat upon the cylinder adapted to hold said collar valve in perpendicular position.

In testimony that I claim the foregoing I have hereto set my hand in the presence 85 of two witnesses, this 16th day of October, 1915.

MARIUS DUVALL.

Witnesses:

A. R. PAXTON,
CORRIN BARNES.
